Primary Examiner — R. Johnson(74) *Attorney, Agent, or Firm* — Stephen Katsaros(57) **CLAIM**

The ornamental design for a drum head tensioning bracket, as shown and described.

DESCRIPTION

FIG. 1 is a perspective front, left and bottom view of a drum head tensioning bracket showing our new design;

FIG. 2 is a perspective front, right and top view thereof;

FIG. 3 is a front view thereof;

FIG. 4 is a back view thereof;

FIG. 5 is a bottom view thereof;

FIG. 6 is a top view thereof;

FIG. 7 is a left view thereof;

FIG. 8 is a right view thereof;

FIG. 9 is the top view of FIG. 6 including reference line 10-10; and,

FIG. 10 is a cross-sectional view taken along line 10-10 in FIG. 9.

The elements shown in broken lines are for illustrative purposes only and form no part of the claimed design.
